UNITED STATES PATENT OFFICE

152,050

DESIGN FOR A SHOWCASE

William A. Yantis, St. Joseph, Mo., assignor to Chase Candy Company, St. Joseph, Mo.

Application May 20, 1946, Serial No. 129,899

Term of patent 14 years

(Cl. D80—11)

To all whom it may concern:

Be it known that I, William A. Yantis, a citizen of the United States, residing at St. Joseph, in the county of Buchanan and State of Missouri, have invented a new, original, and ornamental Design for a Showcase, of which the following is a specification, reference being had to the accompanying drawing, forming part thereof.

The figure is a perspective view of a showcase, showing my new design.

I claim:

The ornamental design for a showcase, as shown and described.

WILLIAM A. YANTIS.
